WAIST CONSTRUCTION FOR PANTS

Elias Leventhal, Cleveland, Ohio

Application September 7, 1933, Serial No. 688,525

1 Claim. (Cl. 2—236)

This invention appertains to new and useful improvements in the art of apparel, and more particularly to a novel waist construction for pants.

5 The principal object of the present invention is to provide a waist construction involving a belt runway which extends substantially around the waist portion of the pants, but terminating at the front and back so as to permit take-up and let-out in making alterations.

Another important object of the present invention is to provide a waist construction for pants wherein a belt rideway is provided substantially around the entire waistline for the purpose of 15 efficiently supporting the pants at all points.

Still another important object of the present invention is to provide a waist construction for pants involving a belt runway and a plurality of shoulder suspender buttons stitched to the waist 20 portion of the pants so that the thread is sewed through a portion of the runway to reinforce the runway construction so as to prevent the belt from pulling through.

These and various other important objects and 25 advantages will become apparent as the following specification is read.

In the drawing:—

Figure 1 represents a fragmentary front elevational view of the improved pants.

30 Figure 2 represents a rear elevational view of the pants.

Figure 3 represents a top plan view looking at the edge portion of the belt runway.

Figure 4 represents a fragmentary enlarged 35 outside elevational view of the waist portion.

Fig. 5 represents a sectional view taken substantially on line 5—5 of Figure 4.

Referring to the drawing wherein like numerals designate like parts, it can be seen that numeral 40 5 generally refers to the trousers of which the legs are denoted by numerals 6—6. The waist portion includes a band 7 and an outer runway defining strip 8. The band and strip are placed together and are stitched to the upper edge of 45 the trousers, as at 9, while the remaining edge portions of the band 7 and strip 8 are stitched together at 10, thus defining a belt runway 11

which terminates at the front of the trousers at the points *a*—*a* and at the back of the pants at points *b*—*b*. At these points *a*—*a* and *b*—*b*, the opposed ends of the runway are spaced so as to accommodate the buckle 12 of the belt 13, at the front of the pants, while the space *b*—*b* at the rear of the pants is to afford principally space to permit alteration at the seam 14.

As it is customary to place suspender buttons on trousers, it can be seen that the buttons 15 are 10 employed to advantage in that the stitching 16 therefore is disposed through the band 7 and strip 8 immediately below the stitching 10 so that the principal weight of the trousers is suspended by the rest of the stitchings 16 against 15 the belt 13. Thus the belt runway is reinforced at its upper edge portion where the main strain is in effect when the trousers are being worn.

Thus it can be seen, that the trousers are supported by the belt at substantially all points 20 around the waistline and that the stitchings 16 of the suspender buttons 15 take up most of the strain, thus relieving the stitching 10 and the upper portions of the band 7 and strip 8 of the belt runway.

While the foregoing specification sets forth the invention in specific terms, it is to be understood that numerous changes in the shape, size and materials may be resorted to without departing from the spirit and scope of the invention as 30 claimed hereinafter.

Having described the invention, what is claimed as new is:—

In a pants construction, a tubular waist portion defining a free belt passageway, said waist portion having an opening therein through which a belt can be inserted for disposition in the passageway, and suspender attaching members stitched to the tubular waist portion adjacent the upper portion thereof, the stitching of the suspender attaching members passing through the belt passageway immediately below the upper portion of the tubular waist portion to relieve the upper portion of the waist portion from some of the strain imposed thereon by the presence of a belt in the passageway.

ELIAS LEVENTHAL.
